HAND-OPERATED WASHING MACHINE

Allen H. Rowlett, Washington, D. C.

Application August 6, 1948, Serial No. 42,977

3 Claims. (Cl. 68—75)

1

This invention relates to a washing machine, and more particularly to a hand-operated washing machine.

An object of the invention is to provide a hand-operated washing machine that will wash clothes quickly and thoroughly.

Another object of the invention is to provide a hand-operated washing machine that can be adjusted to fit various sizes of water containers.

A further object of the invention is to provide a hand-operated washing machine that is extremely simple and inexpensive to manufacture.

Other objects and advantages will be apparent during the course of the following description.

In the accompanying drawings forming a part of this application, and in which like numerals are employed to designate like parts throughout the same:

Figure 1 is an end elevational view of the washing machine according to the invention;

Figure 2 is a sectional view taken on line 2—2 of Figure 1;

Figure 3 is a sectional view taken on line 3—3 of Figure 2;

Figure 4 is a top plan view of the device;

Figure 5 is a sectional view taken on line 5—5 of Figure 2;

Figure 6 is an enlarged elevational view illustrating the means for attaching the slats to the uprights;

Figure 7 is a top plan view of the device of Figure 6.

Referring to the drawings, the washing machine includes a container for clothes comprising a pair of spaced, parallel uprights or end walls designated by the numerals 10 and 11. Each of the uprights is provided with a lower arcuate edge, and extending between the uprights 10 and 11 is a plurality of spaced parallel slats 13. The slats 13 abut the outer edges of the uprights and are secured to the latter, as by nails 14. Extending around the slats 13 are a pair of spaced, parallel metal straps 15, there being nails 12 extending through the straps 15, through the slats 13, and terminating in the uprights to provide an additional securing means for the slats 13 so that the slats will not become loosened from the uprights 10 and 11, during use of the washing machine. The upper ends of each of the straps 15 are bent to define a bracket 16 for embracingly receiving the uppermost of the slats 13, Figures 6 and 7. A nail 17 is driven through the bracket 16 and the slats held thereby and into the complementary upright to prevent loosening of the straps 15 during use of the machine.

2

Secured to the bottom of the upright 10 by a plurality of screws 23, is a base 18 provided with a pair of depending legs 19, and secured to the bottom of the upright 11 by a plurality of screws 23, is a second base 20 provided with a pair of depending legs 21. The legs 19 and 21 support the washing machine and help to prevent the machine from rolling during use.

Each of the uprights 10 and 11 is provided with a plurality of spaced, apertures 22 for the egress and ingress therethrough of water from a tub or receptacle.

The inner faces of the uprights are each provided with a vertically-disposed rectangular groove 24 and 25, respectively, and seated in the grooves 24 and 25 is a pair of complementary metal guide brackets or channels 26 and 27 for a purpose to be hereinafter described.

The washing machine is provided with a stop means that can be adjusted for engagement with a suitable tub 28 adapted to hold water, Figure 4, to thereby maintain the washing machine in an immobile position during use. The stop means comprises a pair of superposed, horizontally-disposed bars 29 and 30 arranged on each side of the washing machine and the bars are each provided with tapered ends 35 and mounted for longitudinal movement relative to each other. The bars 29 and 30 are provided with a slot 31 and 32, respectively. Extending through the slots 31 and 32 and arranged in threaded engagement with the uprights is a pair of threaded bolts 33. Threaded on each of the outer ends of the threaded bolts 33 is a wing nut 34, there being a suitable washer 36 circumscribed on the bolts 33 and interposed between the wing nut 34 and the adjacent bar 29.

The agitator or rubber of the washing machine comprises a pair of vertically-disposed, spaced, parallel circular end walls 37 and 38 positioned between the uprights 10 and 11 of the clothes container. The walls 37 and 38 are each provided with a plurality of spaced apertures 41 for the egress and ingress therethrough of water. A plurality of spaced, parallel slats 39 extend between the walls 37 and 38 and are secured to the outer peripheral edge thereof, as by nails 40. The agitator is mounted for pivotal movement about a horizontal axis, and for causing the pivotal movement a pair of spaced, parallel arms 42 and 43 are secured, as by screws 44, to the end walls 37 and 38, respectively. A rod 45 extends between the upper ends of the arms 42 and 43 and is adapted to be gripped by the operator for actuating the rubber. The pivotal connection

between the agitator and the container comprises a pair of threaded pivot pins 46 and 47 which have one end threaded through the end walls and into the adjacent arms 42 and 43. The other end of each of the pins 46 and 47 is cylindrical and is rotatably seated in the complementary channels 26 and 27.

In use, the washing machine is placed in a tub or receptacle 28 containing water and then supported therein by the legs 19 and 24. The wing nuts 34 are then loosened and the bars 29 and 30 extended until their tapered ends engage the inner surface of the tub 28, and the wing nuts are then tightened so that the washing machine will remain immobile during use. The clothes to be washed are placed on the slats 13 of the washing machine container, and the operator grips the shaft 45 and oscillates or rocks the agitator back and forth. By oscillating the agitator or rubber back and forth, the clothes will be subjected to the rubbing action thereof, and since the agitator pivot pins are free to move up and down in the channels 26 and 27, the slats 29 will follow the curvature of the clothes being washed to not only prevent direct wear to the clothes, but also to permit of sufficient clearance for buttons, hooks and the like on clothes being washed to prevent their being torn out of the garments. The space between the slats 13 of the container, the space between the slats 39 of the agitator, and the apertures 22 and 41 allow ingress and egress of water therethrough between the washing machine and tub 28.

As many embodiments may be made of this invention, and as many modifications may be made in the embodiment hereinbefore shown and described, it is to be understood that all matter herein is to be interpreted merely as illustrative and not in a limiting sense.

I claim:

1. In a washing machine, the combination with a tub, of a container for holding clothes to be washed supported in said tub, said container comprising a pair of spaced, parallel uprights, a plurality of spaced, parallel slats extending between said uprights and secured to the latter, an agitator pivotally connected to said container, said agitator comprising a pair of spaced, parallel end walls interposed between the uprights of said container, a plurality of spaced, parallel slats extending between said end walls and secured thereto for coacting with the slats of said container to wash clothes upon pivotal movement of said agitator, stop means operatively connected to said container for maintaining the latter in an immobile position relative to said tub, said stop means comprising a pair of superposed bars adjustably connected to said uprights and mounted for longitudinal movement relative to each other, means for releasably locking said bars in adjusted position, and manually-operable means operatively connected to said agitator for causing pivotal movement of the latter, the outer ends of said bars adapted to engage said tub.

2. In a washing machine, the combination

with a tub, of a container for holding clothes to be washed supported in said tub, said container comprising a pair of spaced, parallel uprights, a plurality of spaced, parallel slats extending between said uprights and secured to the latter, an agitator pivotally connected to said container, said agitator comprising a pair of spaced, parallel end walls interposed between the uprights of said container, a plurality of spaced, parallel slats extending between said end walls and secured thereto for coacting with the slats of said container to wash clothes upon pivotal movement of said agitator, stop means operatively connected to said container for maintaining the latter in an immobile position relative to said tub, said stop means comprising a pair of superposed bars adjustably connected to said uprights and mounted for longitudinal movement relative to each other, means for releasably locking said bars in adjusted position, and manually-operable means operatively connected to said agitator for causing pivotal movement of the latter, the outer ends of said bars adapted to engage said tub.

3. In a washing machine, the combination with a tub, of a container for holding clothes to be washed supported in said tub, said container comprising a pair of uprights, a plurality of slats extending between said uprights and secured to the latter, an agitator pivotally connected to said container, said agitator comprising a pair of end walls interposed between the uprights of said container, a plurality of slats extending between said end walls and secured thereto for coacting with the slats of said container to wash clothes upon pivotal movement of said agitator, stop means operatively connected to said container for maintaining the latter in an immobile position relative to said tub, said stop means comprising a pair of superposed bars adjustably connected to said uprights and mounted for longitudinal movement relative to each other, means for releasably locking said bars in adjusted position, and manually operable means operatively connected to said agitator for causing pivotal movement of the latter, the outer ends of said bars adapted to engage said tub.
